UNITED STATES PATENT OFFICE

THEOPHIUS O. DUCKWORTH AND FRANCIS L. HORSPOOL, OF SALT LAKE CITY, UTAH

COUNTERBALANCE

Application filed October 17, 1930. Serial No. 489,282.

This invention relates to an improvement in a counter balance. And one of its objects is to provide a counter balance of new principle and different from any known counter balance now in use.

Another object of this invention is to provide a counter balance entirely controlled by air pressure.

Another object of this invention is to provide a counter balance with which the dangerous walking beam and sliding weight now used are abolished.

Another object of this invention is to provide a counter balance controlled by air and constructed in such a manner that a very small amount of power will be required to operate the weight.

Another object of this invention is to provide a counter balance, comprising a plurality of cylinders having pistons therein with which an air cushion will be placed against the piston in the lowering of the weight or the load to be lowered, and to place an air lifting pressure against the piston in the lifting of the weight or load to be raised.

With these and other objects in view the invention consists of the following novel construction as hereinafter described and claimed.

In the accompanying drawing forming a part of this specification and in which corresponding parts are denoted by like reference characters, is illustrated the preferred form of embodiment of the invention capable of carrying the same into practical operation, it being understood that the invention is not necessarily limited thereto, as various changes in shape, proportions and general assemblage of its parts may be resorted to without de-

parting from the principles of the invention, or sacrificing any of its advantages, and the right is therefore reserved for making all the changes and modifications which will fall within the scope of the invention and claim made therefor.

The invention will be described as applied to the Duckworth pump rod lifts, Serial No. 458,103, filed May 31, 1930, or Serial No. 383,949, filed Aug. 6, 1929. When Serial No. 458,103 is used the counter balance 7 and the

support 8 are omitted, while it is shown on the Duckworth pump rod lift it can be applied to any other design of pump rod lift.

Referring to the drawing:

Figure 1 is a plan view of the invention showing it in combination with the Duckworth pump rod lift.

Fig. 2 is a front view of Fig. 1, showing one set of cylinders partly in section to show the construction of the cylinders and pistons.

The reference character A denotes a floor or base plate upon which the invention and pump rod lift B rests. C denotes air tanks which are connected together by a pipe D in such a manner that each tank contains the same air pressure. On top of each tank is placed a safety valve 1 through which all over load of air escapes.

The cylinders E and F are secured to their base G by welding or other means. The base G has an aperture 2 therein into which is placed one end of a pipe H and the other end of the pipe H is secured within the tanks C, thus making a solid air chamber out of the cylinders E, pipes H and the tanks C. The tank C must be not less than forty times the size of the cylinder to give the required air space, so that there will be no back pressure on the piston 3 when the piston is being moved to the lower end of the piston E and but a very small change in pressure when the piston 3 is moved to the upper end of the cylinder E.

The cylinders E are counter balancing cylinders which in combination with the tanks C counterbalance the load carried by the pump rod.

Within the cylinders E is a piston 3 having one end of a piston rod 8 secured therein, the other end of said rod being secured to a cross head J.

The cylinder F which has a piston 4 therein also has valves 5 passing therethrough to allow air to enter said cylinder on the inward stroke of said piston. One end of a piston rod 6 is secured to said piston and the other end thereof being secured to the cross head J. In the inward stroke of said piston 4 the air within the cylinder F is compressed and forced out of the cylinder 100

through valve 7 in the bottom thereof into opening 9 into cylinder E, thus keeping the air in the tanks at the required pressure at all time. And in the event that the pressure would become excessive it will pass out through the relief valve 1 of the tank C.

On the upper ends of the cylinders E and F is secured a flange 10 to which is secured vertical rods 11 the upper ends thereof being secured to a brace 12. The brace 12 is secured to the support 13 and projects outward therefrom. Each vertical rod 11 is placed through an aperture in the forks 14 of the cross head J. They also answer as guides for the crosshead J.

The pump rod lift B used to operate the pistons 8 and 6, comprises a support 13 having notches therein through which is placed horizontal moving rods 15 which are secured into the notches by a plate 16 secured to the upright support 13. On each end of the rods 15 are secured vertically placed rods 17. Each end of the vertically placed rods has a roller bearing 18 thereon. The roller bearing in the lower end of the rods 17 roll back and forth on a track 19 which is secured to the support 13 by bolts 90. The roller bearings on the upper ends of the rods 17 roll back and forth under a track 20 which is secured to the support 13 by bolts 91.

A housing 21 operating up and down on the vertical rods 17 has an endless rack 22 therein secured to the inner wall thereof. A pinion 23 within said housing secured to one end of a shaft 24 passing through said support 13, said pinion meshing with said endless rack. The shaft 24 has a driven wheel 25 on the outer end thereof having a belt thereon attached to a motor K. The motor operates said wheel 25 which operates the shaft 24 and pinion 23 to move the housing up and down and right and left as shown by dotted lines and arrows 93, the housing being connected to the cross head by links 26. Thus as the housing is raised the cross head will be raised to dotted lines L which moves the pistons outward in the cylinders and as the cross head is lowered by the housing the pistons are moved inward of the cylinders.

When the invention is operated as stated above the air in the tanks passing through the pipes H enter the cylinders and coming into contact with the pistons 3 always maintain a pressure against the inner side of the pistons, so when the housing is raised to move the cross heads and pistons outward, the air under the pistons help to raise them.

When the pistons 3 are moved into the cylinders the air within the cylinder is forced back through the pipe H into the tanks, thus forming a cushion under the pistons. The air so entering and maintained within the cylinders forms the counter balance for the

weight of the pump rod M which is in the well N. The pump rod is secured to the cross head in such a manner that it will move up and down with the cross head.

To illustrate the counter balancing ability of the invention in its movements.

Take the piston in the cylinders E to have an area of 58 square inches, and the air pressure in the tank to be 110 pounds per square inch. There would be a pressure of 6380 on each cylinder, or 12760 on the two pistons. This air pressure would hold up a weight of 12760 pounds. The weight of the pump rod and liquid in the well weighing 13000 pounds, leaves a lifting power for the motor to lift of a little better than 240 pounds.

The tank or air reservoir is first filled with air to the required pressure by a portable air pump to the pressure required, and after the invention has been placed in operation it will supply its own air, as stated above.

Having thus described the invention what we claim as new and desire to secure by Letters Patent, is:

An air counterbalance for a pump rod comprising a crosshead secured to said pump rod, means for reciprocating said crosshead, a counterbalancing unit on each end of said crosshead, each counterbalancing unit comprising a reservoir, a main cylinder in combination with said reservoir, an auxiliary supply cylinder having a one-way valve at the end thereof in communication with said main cylinder, pistons in said cylinders and means connecting said pistons to said crosshead.
